Primary Examiner — Robin V Webster(74) Attorney, Agent, or Firm — James L. Young;
Westman, Champlin & Koehler, P.A.(57) **CLAIM**

The ornamental design for a paint container liner, as shown and described.

DESCRIPTION

FIG. 1 is a perspective view of a paint container liner;
FIG. 2 is a left side view of the liner of FIG. 1;
FIG. 3 is a right side view of the liner of FIG. 1;
FIG. 4 is a back view of the liner of FIG. 1;
FIG. 5 is a front view of the liner of FIG. 1;
FIG. 6 is a top view of the liner of FIG. 1; and,
FIG. 7 is a bottom view of the liner of FIG. 1.

The broken line showing of environment is included for the purpose of illustrating and forms no part of the claimed design.

The dot-dashed-dot lines in the FIGS. represent the border between claimed and unclaimed subject matter and form no part of the claimed design.
